UNITED STATES PATENT OFFICE

ROSS HAWKINS, OF CHICAGO, ILLINOIS, ASSIGNOR TO HAROLD E. HAWKINS, OF CHICAGO, ILLINOIS

INDICATING MEANS

Application filed September 26, 1927. Serial No. 221,872.

My invention relates to means adapted to be employed in connection with sheets containing certain data or records; said means providing a visible signal,—having a preselectable value,—whereby a condition or status of the data or items recorded on any given sheet of the record book is indicated to the user, without resort to a mass of records or filed data.

10 My invention, more specifically stated, involves the provision of record-receding sheets, preferably of the loose-leaf type, provided with a multiple of small pockets arranged along one of the marginal edges of each sheet; said pockets being adapted to receive a preselected indicating symbol or signal whereby the condition of the accounts or recorded data on said sheet is immediately conveyed or indicated to the user.

20 The invention has for its object the provision of a plurality of individual pockets along the marginal edges of the sheets of a loose-leaf book wherein the sheets are arranged in an overlapping relation so that a 25 marginal edge of each sheet is uncovered and visible; the respective pockets being perforated or each provided with an opening through which the symbol or signal is visible and removal from the pocket of the symbol or signal media made unnecessary; the 30 pocket-forming element being preferably of suitable transparent or translucent material whereby greater visibility of the signals is provided.

35 The invention also has for its object the provision of a plurality of individual pockets formed to permit a change of any or all of the symbols or signals to be readily made without mutilation of the sheets, thus providing 40 for greater flexibility or scope of the record; while at the same time the marginal pocket-forming means tends to reenforce the sheets and assists in maintaining proper alignment 45 of the overlapping sheets in the loose-leaf binder or holder.

The above enumerated objects and advantages, as well as other advantages inherent in the invention, will all be more fully comprehended from the following description of

the embodiment of the invention as disclosed in the drawings, wherein:

Figure 1 is a plan view of a loose-leaf holder or binder wherein the record-containing sheets are arranged in overlapping relation 55 and each provided with my improved means.

Figure 2 is a plan view of one of the sheets, on an enlarged scale, to more clearly disclose the invention.

Figure 3 is a similar view of a portion of a 60 sheet, illustrating a modification of the invention.

In the particular exemplification of the invention, 10 represents a holder or binder provided with rings 11 which may be of any suitable well-known type and formed to permit the same to pass through the perforations 12 of the respective sheets. As the binder or holder is of a well-known construction, further detailed description thereof need not be 65 entered into.

Record binders or holders of this type are provided with a multiple of sheet-holding elements as shown in Figure 1, for the purpose of receiving short sheets or cards, indicated at 13 which may be ruled and provided with any desired forms to suit requirements.

In the particular exemplification, the sheets are arranged in overlapping relation 80 at the bottom edges of the sheets; the sheets or cards adapted for use in this type of binder being provided with a plurality of perforations 12 preferably arranged along the inner vertical edge of the sheet to receive 85 the holding elements 11.

That is to say, the sheets are arranged so that the lower marginal edge of the succeeding sheets will be exposed beyond the lower edge of the preceding sheet or superposed card. If desired, of course, the arrangement may be reversed by having the topmost sheet at the bottom of the stack and lapping the succeeding sheets so as to expose the upper longitudinal margin of the successive sheets, 90 in which event my improved means is then applied to the upper longitudinal edge of each sheet instead of to the lower longitudinal edge as shown in the drawing.

My invention consists in providing the ex- 100

posed longitudinal margins of the respective sheets with a plurality of symbol or signal receiving pockets which may be formed by providing each sheet with a longitudinal marginal portion adapted to be folded onto the forward or record-keeping side of the sheet. These pockets, however, are preferably formed by employing comparatively thin strips 14 of transparent or translucent material, provided with any desired number and shape of apertures as at 15 in Figures 1 and 2, or as at 16 in Figure 3. The strips 14 are then secured to the exposed longitudinal margin of the respective sheets at points intermediate of the apertures 15 or 16, as the case may be; the strips being secured at the various spaced points by means of a suitable adhesive substance or glue, so as to leave the perforated portions unattached to the record sheets, except at the lower longitudinal edge of the strip which is also secured to the record sheet, while the upper longitudinal edge of the strip, particularly immediately above the perforations, is left unattached, thus providing a plurality of pockets coinciding with the perforations 15 or 16.

These pockets are adapted to receive small pieces of colored material or card-board, preferably cut from thin sheets of celluloid; the various inserts, in order to constitute a signal which is quickly discernible, being preferably of different preselected colors. For example, in Figure 2, 17 indicates a red insert; 18 indicates a blue insert; 19 an orange-colored insert; 20 a brown-colored insert; 21 a green; 22 a black insert; and 23 a yellow insert.

It will be understood that any number of colors or combination of colors may be used; each color constituting a visible signal designating a certain condition or status of the record or data on the sheet; the respective colors having a value or constituting a signal in keeping with a predetermined code or key. The various symbols or signal slips, indicated at 17 to 23 in the particular exemplification, are removably held in their respective pockets, thus permitting the same to be quickly removed or replaced in keeping with the changing conditions of the matter recorded on the sheets or cards. With my invention, the signals may constantly be altered in keeping with conditions of any particular record sheet as long as said sheet is in use and these changes can be made without in any way mutilating the sheet.

The pocket-forming strip or portion 14 is also shown provided with an elongated or large aperture or opening 24 in the end pocket which is adapted to receive a slip containing the name of the customer or data recorded on said sheet. If desired, the end of the strip where this enlarged pocket is located, may merely be fastened or glued at the immediate corners, namely at the points indi-

cated at 25, 26, thus leaving an opening or unattached portion intermediate of the points 25, 26, for the lengthwise insertion of a large slip containing the name of an individual or customer or name of the subject-matter recorded on the sheet.

As previously stated, the binders are made to contain a plurality of narrow or short sheets in order that the latter may be arranged in overlapping relation as shown in Figure 1, so as to expose a longitudinal margin of each sheet; preferably the lower longitudinal margin. By providing this lower longitudinal margin with a strip of thin material, of width substantially equal to the width of the exposed lower margins of the sheets (except on the topmost sheet where the strip may be slightly wider), the edge of each individual sheet is not only reinforced, but an abutting shoulder or edge is also provided for the lower edge of the superposed sheet, which assists in maintaining proper alignment of the sheets and therefore tends to prevent a sloping position of the superposed sheets or pile.

With the pocket-providing strip 14 made of thin sheet material, such as thin transparent paper or similar material, the flexibility of the record sheets is in no way affected; the thin transparent material increasing visibility of the signal; while the individual pocket for each symbol or signal provides a very flexible signal method or control which permits the record to serve for various purposes or information.

Instead of providing the pockets with the circular apertures 15 as shown in Figures 1 and 2, the apertures may be of different configuration, as for example rectangular as shown in Figure 3.

Furthermore, the colored inserts or signal slips may be cut to any desired shape so as to present a different appearance or signal, thus increasing the scope of the visible signal or method. For example, at 27 in Figure 2 and at 28 in Figure 3, I show the signal slips or inserts of triangular shape and of pre-selected color.

My improved indicating means or visible signal control constitutes a time-saving method through the substitution of sight, as it were, for labor in searching numerous records, thereby providing data or a record available to an executive whereby full knowledge of the condition of the business or of any department thereof may be quickly ascertained. For example, the indicating means may be employed with a sales record to indicate the salesmen who call on the territory; which departments are showing business; when the business drops off; credits that are bad; accounts which are not selling as they should; etc., thus enabling a sales manager of a business divided into different departments to obtain information as to the

exact status of each department without resort to a search through voluminous records; in other words, the individual, by reason of the charting of the vital facts by means of the visible signals, will obtain a bird's eye-view of the main facts of the business or department.

The invention has been illustrated in what is believed to be simple adaptations and has been described in terms which have been employed merely as terms of description and not as terms of limitation, as modifications are possible and may be made without, however, departing from the spirit of my invention.

What I claim is:

1. Indicating means of the character described comprising a record or data receiving sheet, one marginal edge whereof is provided with a plurality of pockets open at one side, each pocket being provided with a sight-opening, and signaling slips insertible in said pockets.

2. Indicating means comprising a record sheet provided along a marginal edge with a transparent flexible strip secured at its bottom and ends to said sheet, said strip having holes at points spaced apart lengthwise of the strip, the strip being secured to the sheet at points intermediate of said holes to provide a plurality of pockets, and indicating slips conforming with the configuration of the pockets so as to be insertable in said pockets.

3. In combination with a loose leaf binder, a plurality of sheets arranged in the binder so as to expose the lower marginal edge of each subjacent sheet, a strip of thin flexible material disposed throughout the lower marginal edge of each sheet and of width corresponding with the width of the exposed marginal edge of each sheet so as to maintain alignment of the superposed sheets, each of said strips being secured to the sheet at various points so as to provide a plurality of uniform pockets open at one longitudinal edge of the strip, each pocket being formed to permit visibility of its contents.

4. In combination with a loose leaf binder, a plurality of sheets arranged in the binder in overlapping relation so as to expose a uniform marginal portion of the lower part of each succeeding subjacent sheet, a thin flexible strip of width substantially equal to the width of the lower exposed margin of each sheet secured lengthwise of the lower marginal edge of each sheet so as to permit the superposed sheets to nest with their lower edges resting against the top edge of the strip on the succeeding subjacent sheet, the strip being provided with apertures spaced apart lengthwise of the strip with the strips secured to the sheets at the bottom and ends of the strips and at points intermediate of adjacent apertures in the strips to provide a plurality of pockets along the marginal edge

of each sheet open at the longitudinal edge of the strip, and signaling means of size conforming substantially to the inner dimensions of the respective pockets so as to be wholly insertible in said pockets and visible through said apertures.

ROSS HAWKINS.
